ADVERTISING DISPLAY APPARATUS

Claud E. McCallum, Miami, Fla., assignor of one-half to Frederick Otto Weissenburg and one-half to Frank William Pickard, both of Miami, Fla.

Application February 8, 1938, Serial No. 189,382

6 Claims. (Cl. 40—37)

My invention relates to improvements in advertising display apparatus for use either as roadside installation, window display equipment, a toy, or in any other form favorable for displaying advertising matter.

An important object of the invention is to provide a realistic display apparatus for advertising a particular make of automobile and embodying a pictorial representation, on an attractive background, of the make of automobile but having real wheels adapted to be revolved, together with both a wind and motor operated drive for the wheels, the former controlling the latter so that when the wind dies down the latter is rendered operative and vice versa.

Another object is to provide apparatus of the character and for the purpose above set forth equipped with an intermittently sounding horn and flash illumination operative under control of the drive, and also with means for presenting to view successively varying advertising slogans or other reading matter.

To the accomplishment of the foregoing, and subordinate objects presently appearing, a preferred embodiment of my invention has been illustrated in the accompanying drawings, treated in detail in the succeeding description, and defined in the claims appended hereto.

In said drawings:—

30 Figure 1 is a view in front elevation of apparatus constructed in accordance with my invention.

Figure 2 is a view in rear elevation of the casing with the closure panel removed.

Figure 3 is a view in vertical transverse section taken on the line 3—3 of Figure 2 looking in the direction indicated by the arrows,

Figure 4 is a fragmentary view in vertical section taken on the line 4—4 of Figure 3 looking in the direction indicated by the arrows,

40 Figure 5 is a fragmentary view in vertical transverse taken on the line 5—5 of Figure 2 looking in the direction indicated by the arrows and drawn to an enlarged scale, and

Figure 6 is a diagrammatic view of the circuits.

45 Referring to the drawings by numerals, the basic element of my invention comprises a shallow, preferably rectangular, casing 1 adapted to be disposed in upright position and lengthwise upon suitable supports, not shown, and including 50 a topside 2, a bottomside 3, ends 4, a front panel 6 and a rear panel 5 the latter hinged as at 7 to the bottomside 3 to form a closure for the casing to be locked in closing position by means of a suitable catch indicated at 8. The casing 1 55 may be formed of any suitable material such as

wood, sheet iron, or the like. The front panel 6 has depicted thereon, along the lower part thereof, a suitable background 9 and an automobile 10 in the foreground having a pair of front and rear wheels 11 and 12 respectively, the automobile 10 being centered on the panel 5 so that the wheels 11 and 12 are disposed upon opposite sides of the vertical center of the casing 1 respectively.

The wheels 11 and 12 are disks, of any suitable material, disposed close to the panel 6 just clear 10 of the front face of the latter and fast upon a pair of front and rear spindles 13 and 14 extending through suitable bearings, as at 15, provided in the panel 6 and having rear ends journaled in U-shaped bearing brackets 16 in the casing 1 15 bolted to the rear face of the panel 6 as at 17. Preferably the bearings 15 and the bearing brackets 16 are equipped with ball bearing assemblies as indicated at 18 and 19. The spindles 13 and 14 each have fast thereon, intermediate the panel 6 20 and bearing brackets 16, a pulley 20 for driving the spindles in a manner presently described. Each spindle 13, 14 also has fast thereon a collar 21 coacting with the bearings 15 to limit outward movement of the wheels 13 or 14 as the case may 25 be.

The pulleys 20 are adapted to be driven by the following drive mechanism:

In the vertical center of the casing 1 is a vertically disposed primary drive shaft 21 extended downwardly into said casing by way of a bearing sleeve 22 upstanding from the topside 2 of said casing, said shaft also extending through a suitable ball bearing assembly 23 in said topside 2 and terminating in the upper part of said 30 casing. The upper end of the primary drive shaft 21 is equipped with a suitable head 24 seating against a suitable end thrust bearing 25 on said sleeve 22 and having radiating therefrom a plurality of arms 26 equipped at their outer ends 35 with suitable cup-like vanes 27 and forming together with said arms 26 and head 24 a wind wheel for driving said shaft 21. Below the primary drive shaft 21 is a secondary drive shaft 28 40 axially aligned with the shaft 21 and having its lower end journaled in a bearing bracket 29 upstanding from the bottomside 3 in the casing 1 and suitably secured to said side as at 30. The upper end of the secondary drive shaft 28 extends through a suitable anti-friction bearing 31 45 from the panel 6 and terminates short of the lower end of the primary drive shaft 21.

The primary drive shaft 21 is adapted to be operatively connected to the secondary drive 50 shaft 28.

shaft 28 by means of the following clutch mechanism:

Fast on the lower end of the primary drive shaft 21 is a clutch disk 32 having a lower clutch facing 33 opposed to a similar clutch facing 34 on another clutch disk 35 subjacent to the clutch disk 32 and fast upon a clutch rod 36 intermediate the ends of the latter. The clutch rod 36 has its opposite ends telescopically mounted in the lower end of shaft 21 and upper end of shaft 28, respectively, for vertical sliding movement therein whereby under such movement of said rod in opposite directions the clutch disk 35 may be engaged with and disengaged from the clutch disk 32, respectively, as will be readily understood. The lower end of the clutch rod 36 is splined in the upper end of the secondary drive shaft 28 as indicated at 37 and rotatable in the lower end of the primary drive shaft 21. The clutch rod 36 is moved in opposite directions respectively under control of a centrifugal throw governor as follows: Fast on the said shaft 21 in surrounding relation to the upper end of the clutch rod 36 is a sleeve 38 bolted to said shaft as at 39 and having a lower slotted flange 40 in which is pivoted as at 41 a pair of governor arms 42 the arrangement being such that said arms 42 are vertically swingable on their inner ends in said flange. The governor arms 42 are equipped at their outer ends with the usual ball members 43. The pivoted ends of the governor arms 42 terminate in a pair of cams 44 operatively engaging the underside of a rod-operating yoke 45 rotatable about the upper end of the clutch rod 36 and rabbeted in the same as indicated at 46, said yoke extending through suitable slots 47 and 48 in the shaft 21 and sleeve 38 respectively so that it is vertically movable independently to impart similar movement to said clutch rod. The arrangement of the described parts is such that the clutch arms 42 normally gravitate into substantially vertical position and the yoke 45 and clutch rod 36 are supported by said cams 44 in a position such that the clutch disk 35 is disengaged from the clutch disk 32. Under rotation of the shaft 21 the clutch arms 42 are swung upwardly, in the usual manner, under centrifugal throw of the ball members 43, under which action of the arms 42 the cams 44 elevate the yoke 45 and clutch rod 36 to engage the clutch disk 35 with the clutch disk 32. In this connection it is to be noted that the cams 44 are substantially heart-shaped and so arranged relative to the yoke 45 that when the governor arms 42 have moved upwardly in a predetermined degree, said cams 44 will permit the yoke 45 and clutch rod 36 to descend and disengage the disk 35 from the disk 32. This is a safety provision for preventing operation of the secondary shaft 28 when the wind attains undue velocity.

The lower end of the secondary drive shaft 28 is operatively connected, by means of bevelled gearing 49, to a horizontally extending jack shaft 50 journaled in anti-friction bearings 51 and 52 provided in the beforementioned bearing bracket 29 and panel 6 respectively. The jack shaft 50 has fast thereon a pair of pulleys 53 connected by belts 54 to the beforementioned pulleys 20 respectively.

Describing now the slogan displaying features of the invention, the panel 6 has formed therein above the background 9, which is to say in the upper part of said panel, a horizontally elongated aperture 55 covered by a glass panel 56 and

surrounded by a retaining frame 57. Adjacent each end of the aperture 55 is a pair of upper and lower bearing brackets 58. A pair of convex rollers 58 are journaled in upstanding positions in said pairs of brackets 58, respectively, by means of studs 59 on said rollers, the rollers extending across opposite ends of said aperture 55 and having trained around the same an endless band 60, of any suitable material, upon which is printed or otherwise delineated suitable slogans or legends as at 61, so that upon rotation of said rollers said slogans will be rendered visible, successively, through said panel 56. One of the rollers 58 is revolved by the secondary drive shaft 28 through the medium of a pair of pulleys 62 and 63 fast on said shaft and one of the studs 59 of said roller, respectively, and a belt 64 extending between said pulleys.

Extending forwardly and downwardly from the top of the frame 1 is a pair of suitable reflector supports 65 provided with reflectors 66 and located adjacent opposite ends of the panel 56 respectively. Within the reflectors 66 are electric light bulbs 67 secured therein in any suitable manner.

Suitably secured to the front panel within the casing 1 is an automobile horn 68 of the electrically operated type and which together with the electric light bulbs 67 is adapted to be intermittently energized by means to be described in detail and including a pair of resilient contact blades 69 and 70 adapted to be bridged by a revolving contact pin 71 upstanding from a gear wheel 72 fast on an arbor 73 journaled at its opposite ends in a bearing bracket 74 secured to the panel 6, as at 75, said gear wheel 72 meshing with a smaller gear wheel 76 fast on the secondary drive shaft 28 whereby said shaft 28 drives gear 72 and the revolving contact 71 intermittently bridges the resilient contact 69 and 70 to intermittently close the circuits, in a manner presently clear, and correspondingly energize the light bulbs 67 and horn 68.

Under normal conditions, that is when wind is available to operate the described wind wheel 45 the apparatus is driven by said wind wheel and the electric lights 67 and horn 68 are energized by a battery 77 under control of the described contacts 69 and 70 and revolving contact 71. However, when no wind is available, or the wind 50 attains undue velocity and the clutch disks 35 and 32 are disengaged in the manner previously described, the apparatus is driven by a motor 78 mounted on top of a housing 79 secured to the bottomside 3 of the casing, in the latter, and operatively connected to the jack shaft 50 by means of a pair of pulleys 80 and 81 fast on the armature shaft 82 of said motor and said jack shaft, respectively, and a belt 83 connecting said pulleys. Also under normal conditions such as mentioned the battery 79 is charged by means of a generator 84 suitably secured in the casing 1 to the panel 6, as indicated at 85 and operated by the primary drive shaft 21 which shaft comprises the armature shaft of the generator.

The wiring for the apparatus comprises the following:

One side of the generator 84 is connected by a lead 86 to the battery 77 through a suitable cut-out 87 to one side of which said lead 86 is connected, the other side of the cut-out being appropriately connected to the positive and negative poles 88 and 89 of said battery with a condenser 90 interposed in the line of connection between said cut-out and pole 89. The electric 75

lights 77 are connected on one side by a lead 91 and on the other by a lead 92, the lead 91 being wired as at 93 to the minus pole 89 of said battery and the lead 92 being wired by a lead 94 to the contact 69 which is adapted to be bridged to the contact 70 which is connected by a lead 95 to the positive pole 88 of said battery. The other side of the generator 84 is connected to the lead 93 by the short lead 96. The horn 68 is connected on one side by a lead 97 to lead 93 and on the other side by a lead 98 to lead 94. As will be seen under normal conditions, the generator 84 energizes the battery 77 by way of lead 86 and cut-out 87 the latter operating when the battery 77 is fully charged to cut out the generator 84. Also each time the contacts 69 and 70 are bridged by the revolving contact 71 the electric lights 67 are energized by way of lead 95, contacts 70, 71 and 69, leads 94 and 92, and 20 leads 91 and 93. Coincidentally the horn 68 is energized by way of leads 98 and 97 in a manner which will be manifest.

As we have already seen when no wind is available and the governor arms 42 are in pendant or substantially vertical position the clutch disk 35 is disengaged from the clutch disk 32. Likewise, when the wind attains undue velocity a similar situation obtains. Under these conditions the motor 78 is rendered effective to drive the 30 jack shaft 50 and secondary drive shaft 28, to drive the apparatus, and by the following means. When the clutch disk 35 descends to disengaging position an annular shoe 99 secured to the underside of said disk 35 against an insulation strip 35 100 bridges a pair of fixed contacts 101 and 102 suitably secured, as at 103, to the front panel 6 within the casing 1 and controlling operation of the motor 78. One of the contacts, 101, is wired by a lead 104 to the positive pole 88 of the battery 40 77. The other contact 102 is wired by a lead 105 to one side of the motor 77 the other side of which is connected by a short lead 106 to the aforementioned lead 93. Consequently when the contacts 101 and 102 are bridged by the shoe 99, 45 it being understood that the latter is of conductive material, the motor 78 is energized from the battery 77 by way of lead 104, contacts 101, 102, lead 105, short lead 106, and lead 93 to the minus pole 89 of the battery. Obviously, under 50 centrifugal throw of the ball members 43 and upward swinging of the governor arms 42, under which movements of said arms 42 to a predetermined point the disks 35 and 32 are engaged, the contacts 101 and 102 are isolated and the 55 motor 78 rendered idle.

The housing 79 contains a clock 107 operatively connected in any suitable manner in the circuit wiring for the lights 67 to cut off said lights at sunset and cut them in again at sunrise.

Since the operation of my invention has been set forth in detail in connection with the foregoing description of parts, it is thought that further explanation as regards operation is not necessary to a clear understanding of the invention.

Manifestly my invention, as described, is susceptible of modification without departing from the inventive concept and right is herein reserved to all such modifications falling within the scope 70 of the subjoined claims.

What I claim is:—

1. Apparatus of the class described comprising a casing having depicted on one face thereof an automobile including wheels, said wheels com-

prising rotatable disks, and a drive for said disks including a wind wheel on top of said casing, a normally ineffective motor in said casing, and operating connections between said disks and said wind wheel and motor, respectively, including a 5 governor operative when the wind wheel is idle to render the motor effective.

2. Apparatus of the class described comprising a casing having depicted on one face thereof an automobile including wheels, said wheels comprising rotatable disks, and a drive for said disks including a wind wheel on top of the casing, a normally ineffective motor in said casing, and operating connections between said disks and said wind wheel and motor, respectively, including 10 a governor operative under rotation of said wind wheel beyond a fixed speed limit to render the motor effective.

3. Apparatus of the class described comprising a casing having depicted on one face thereof an 20 automobile including wheels, said wheels comprising rotatable disks, and a drive for said disks including a wind wheel on top of the casing, a normally ineffective motor, a battery for operating the motor, operating connections between 25 said disks and the wind wheel and motor, respectively, including a governor operative when the wind wheel is idle to render the motor effective, and a generator operative by the wind wheel to charge the battery.

4. Apparatus of the class described comprising a casing having depicted on one face thereof an automobile including wheels, said wheels comprising rotatable disks, and a drive for said disks including a wind wheel on top of the casing, a normally ineffective motor, a battery for operating the motor, operating connections between 35 said disks and the wind wheel and motor, respectively, including a governor operative when the wind wheel is idle to render the motor effective, and a generator operative by the wind wheel to charge the battery, an electrically operative sound-producing device in said casing adapted to be connected in circuit with said battery, and a circuit maker and breaker in said casing operative intermittently as an incident to operation of said drive to control said circuit.

5. Apparatus of the class described comprising a casing having depicted on one face thereof an automobile having wheels, the wheels comprising rotatable disks, and a drive for said disks including a wind wheel on top of the casing, a normally ineffective motor in said casing, a battery for energizing said motor, and operating connections between said disks and said wind wheel and motor, respectively, including a 50 governor operative when the wind wheel is idle to render the motor effective, an electrically operative sound-producing device in the casing, electric lights on the casing for illuminating said face 55 thereof, leads for connecting said device and lights in circuit with said battery, and a circuit maker and breaker operative by said drive to intermittently break the circuits of said device and lights.

6. In apparatus of the class described, a casing-like billboard having depicted thereon an article to be advertised including a movable part, a wind wheel on top of said board, and an electrically operative drive for said part enclosed in 60 the billboard and operative under control of said wind wheel.

CLAUD E. McCALLUM.
